UNITED STATES PATENT OFFICE.

DANIEL H. GAIL, OF BURLINGTON, IOWA, ASSIGNOR TO SOLOMON McNEILL
AND RICHARD S. MCENTIRE, OF SAME PLACE, ONE-THIRD TO EACH.

MACHINE FOR FORMING CONICAL WIRE SPRINGS.

SPECIFICATION forming part of Letters Patent No. 228,624, dated June 8, 1880.

Application filed March 31, 1880. (No model.)

To all whom it may concern:

Be it known that I, DANIEL H. GAIL, a citizen of the United States, residing at Burlington, in the county of Des Moines and State of Iowa, have invented certain new and useful Improvements in Machines for Coiling Conical Wire Springs; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

My invention relates to improvements in machines for coiling conoidal or conical spiral metallic springs in pairs, in which the two springs of each pair are side by side and are formed of a single wire which connects them at their bases; and the objects of my improvements are, first, to afford facilities for coiling the wire from both ends at the same time on conoidal grooved mandrels journaled at fixed distances apart, about equal to the distance between the springs of each pair when completed; second, to provide means of rotating both coiling-mandrels from the same drive-shaft; third, to provide a pair of conical rollers for pressing the springs into the grooves of the mandrel as they are coiled thereon; fourth, to provide means for moving the press-rollers to and from the coiling-mandrels; fifth, to provide means of securing the ends of the wire to the coiling-mandrels, so that they can be released when the coils are formed. I attain these objects by the mechanism illustrated in the accompanying drawings, in which—

Figure 1 is a perspective of the entire machine. Fig. 2 is a top plan. Fig. 3 is a side elevation. Fig. 4 is an end elevation. Fig. 5 is a plan of the hinged press-roller carrier. Fig. 6 is a detail view, hereinafter referred to. Figs. 7 and 8 are, respectively, a plan and elevation of a completed spring.

Referring to the drawings by letters, the same letter indicating the same part in the different figures, letter A represents a base, with blocks B C C', which support the working parts. The base A may be as shown, so that it can be at-

tached where desired, or it may be the top of 50 a suitable table.

D D are conical mandrels, fixed with their base ends each to a separate shaft, E, which shafts are journaled in suitable bearings in the blocks B C, and provided each with a 55 pinion, E', both of which pinions gear with a spur-pinion, F', which is carried on a shaft, F. The shaft F is also journaled in suitable bearings in the blocks B C, and may be rotated by a crank, F'', or by connection with any 60 suitable power. Each mandrel D has a spiral groove, d, formed in its exterior, and a hole, d', in its apex end, and the spiral grooves d terminate at the small end of the mandrel, preferably with a shoulder, d''. 65

G is a frame below the mandrels D, and is hinged at one side to the block C. The frame G has slots g transversely to the mandrels D. H H' H' are standards, which may be adjusted laterally on the frame G, and retained 70 after adjustment by the bolts h, which pass through the slots g. I I are conical press-rollers, journaled at their base ends in the standards H, and at their apexes in the standards H'. 75

J J' are toggle-arms, hinged to each other at j. The arm J is hinged at its upper part to the outer or free side of the frame G, and the arm J' is hinged at its lower part to the block C', so that the outer side of the frame G will drop by gravity to the position shown by full 80 lines at Fig. 3, and thus remove the press-rolls some distance from contact with the mandrels D while in their normal position.

K is a tubular wire-holder, with one side cut away for about one-half of its length, as shown 85 at Fig. 6, which is a perspective thereof, with a wire, L, inserted therein.

In operation, the wires L are cut in proper lengths, and their ends l bent as shown in the drawings. The ends l are inserted in the 90 holders K, as shown at Fig. 6, and the holders K then inserted, one in each hole d' in the mandrels D, as shown at Fig. 1. The mandrels D may then be simultaneously rotated by the shaft F to coil the wire in the grooves 95 d, and the operator, by pressing with his leg against the toggle J J', may force the press-rolls I upward against the wire as it is coiled

and press it into the grooves d , the wire being guided to the grooves d properly by hand, and to both mandrels at one time, until it is all wound thereon, except the central part, L' , as shown by dotted lines at Fig. 1.

By lowering the press-rolls I , as hereinbefore described, and withdrawing the holders K , the coils may be easily removed from the mandrels D , and will be as shown at Figs. 7 and 8.

The toggle $J J'$ may be operated by a foot-pedal, if preferred.

Having thus described my invention, what I claim as new, and desire to secure by Letters 15 Patent, is—

1. In a machine for forming conical wire springs, the conoidal grooved mandrels D , arranged near to each other, and intermediate connecting mechanism, whereby said mandrels 20 are adapted to be simultaneously rotated to form both coils of a double-conical spiral spring from one drive-shaft, substantially as described, and for the purpose specified.

2. In a machine for forming conical wire 25 springs, the combination, with the conical grooved mandrels D and shafts E , having pinions E' , of the shaft F , having pinion F' , and adapted to impart simultaneous rotary movement to the mandrels D , substantially as and 30 for the purpose specified.

3. In a machine for forming conical wire 35 springs, the combination, with the conical grooved mandrels D , of the conical press-rolls I , adapted to press the wire into the grooves d , substantially as and for the purpose specified.

4. In a machine for forming conical wire springs, the combination, with the conical grooved mandrels D , of the conical press-rolls I and hinged frame G , adapted to move the rolls I toward and from the mandrels D , substantially as and for the purpose specified. 40

5. In a machine for forming conical wire springs, the combination, with the conical grooved mandrels D , of the press-rolls I and 45 hinged frame G , to which the press-rolls are attached so as to be adjusted laterally, substantially as and for the purpose specified.

6. In a machine for forming conical wire springs, the combination, with the grooved 50 mandrels D , of the press-rolls I and hinged frame G , the toggle $J J'$, adapted to raise and lower the frame G , and rolls I , substantially as and for the purpose specified.

7. In a machine for forming conical wire 55 springs, the combination of a conical grooved mandrel, D , having a hole, d' , in its apex, and a tubular wire-holder, K , having one side cut away for about one-half its length, whereby it is adapted to hold the wire directly in the 60 mandrel, and to be removed to release it when the coil is formed, substantially in the manner herein shown and described.

In testimony whereof I affix my signature in presence of two witnesses.

DANIEL H. GAIL.
